United States Patent Office

Des. 193,770
Patented Oct. 9, 1962

193,770

SERVICE STATION BUILDING OR THE LIKE

Albert M. Shotmeyer, 371 Sicomac Ave., Wyckoff, N.J.

Filed May 22, 1961, Ser. No. 65,281

Term of patent 14 years

(Cl. D13—1)

FIG 4

FIGURE 1 is a front elevation of a service station building or the like showing my new design;

FIGURE 2 is a rear elevation thereof;

FIGURES 3 and 4 are side elevations, respectively, of the design; and

FIGURE 5 is a top plan view of the design.

While only portions of the roof pattern of the design have been depicted in a manner to indicate a conventional shingle-like appearance, it is to be understood that the entire roof pattern is of said appearance in the several views.

I claim:

The ornamental design for a service station building or the like, substantially as shown and described.
